UNITED STATES PATENT OFFICE

135,445

DESIGN FOR AN APRON

Olive L. Heimerman, Fond du Lac, Wis.

Application February 2, 1943, Serial No. 109,409

Term of patent 7 years

To all whom it may concern:

Be it known that I, Olive L. Heimerman, a citizen of the United States, residing at Fond du Lac, in the county of Fond du Lac and State of Wisconsin, have invented a new, original, and ornamental Design for an Apron, of which the following is a specification, reference being had to the accompanying drawing, forming a part thereof.

The figure is a plan view of an apron, showing my new design.

I claim:

The ornamental design for an apron, as shown.
OLIVE L. HEIMERMAN.
